PROCESS FOR MAKING TETRAETHYL LEAD

Nelson Whitman, Wilmington, Del., assignor to
 E. I. du Pont de Nemours & Company, Wil-
 mington, Del., a corporation of Delaware

No Drawing. Application February 14, 1952,
 Serial No. 271,630

4 Claims. (Cl. 260—437)

1

This invention relates to a process for the manufacture of tetraethyl lead and more particularly to a process for improving the yields of tetraethyl lead.

Tetraethyl lead is a valuable compound which has been manufactured on a large scale for many years. The demand for it is continually increasing and hence the production has increased accordingly and now amounts to millions of pounds a month. Accordingly, even slight improvements in yield, amounting to only a fraction of a per cent, are important commercially and economically.

Tetraethyl lead is made by reacting ethyl chloride with lead monosodium alloy (NaPb). For many years, the process was carried out at temperatures of from about 65° C. to about 85° C. with yields of tetraethyl lead of about 75% to about 85%, such process ordinarily requiring reaction periods of 5 or more hours for completion. George E. Holbrook, in Patent No. 2,464,397, has disclosed that such reaction can be accelerated and the yield of tetraethyl lead increased to the range of about 85% to about 90% by carrying out such reaction in the presence of from about 0.005% to about 4% by weight based on the ethyl chloride of a ketone, preferably acetone. By the use of such ketones, particularly acetone, the reaction period is reduced to less than 2 hours, usually about 90 minutes. For some years, the commercial manufacture of tetraethyl lead has been carried out in the presence of acetone in accordance with the teachings of Holbrook.

It is an object of the present invention to provide an improved process for manufacturing tetraethyl lead. A further object is to provide a method for increasing the yields of tetraethyl lead over those obtained by the processes heretofore employed. Other objects are to advance a art. Still other objects will appear hereinafter.

The above and other objects may be accomplished in accordance with my invention which comprises carrying out the reaction of ethyl chloride on lead monosodium alloy in the presence of from about 0.005% to about 4% by weight of acetone and of from about 0.005% to about 0.06% by weight of acetylene, both based on the weight of ethyl chloride present. By such process, the yield of tetraethyl lead is significantly increased.

It has been found that, when it is attempted to react ethyl chloride with lead monosodium alloy in the presence of acetylene and in the absence of acetone and like accelerating agents, the yield of tetraethyl lead is appreciably decreased.

2

However, I have found that, when such reaction is carried out in the presence of both acetone and acetylene, the yields are increased. Such latter result was entirely unexpected and contrary to that which could be predicted.

The amount of acetone employed may vary from about 0.005% to about 4% by weight based on the ethyl chloride and, preferably, from about 0.1% to about 0.4% by weight.

10 The acetylene may vary from about 0.005% to about 0.06% by weight based on the ethyl chloride and, preferably, from about 0.01% to about 0.03% by weight.

15 The acetone and the acetylene may be added in any desired manner, but, ordinarily, will be dissolved in the ethyl chloride before the ethyl chloride is brought into contact with the alloy.

20 My process may be carried out in the equipment and under the conditions of temperature and pressure which have been heretofore employed in the manufacture of tetraethyl lead and which are well known to the art. Preferably, the process will be carried out at temperatures of

25 from about 80° C. to about 120° C. and corresponding pressures of from about 107 to about 255 pounds per square inch absolute, employing ethyl chloride in excess of the amount theoretically required for the reaction and up to about 4 times the weight of the alloy. The alloy cor-

30 responds closely to the composition NaPb, ordinarily containing between 9.9 and 10.1% of sodium by weight and, preferably, exactly 10% by weight of sodium. The process may be carried out in batches or continuously, the higher temperatures and pressures and the higher proportions of ethyl chloride usually being employed in the continuous process.

35 In order to more clearly illustrate my invention, preferred modes of carrying the same into effect and the advantageous results to be obtained thereby, the following example is given:

EXAMPLE

The following reactions were carried out in 45 steel bombs (capacity about 150 ml.) to which were added between 41 g. and 44 g. of lead monosodium alloy, NaPb (screened to pass 10 mesh but retained on 16 mesh), contained in sealed glass bulbs and ethyl chloride in a proportion of 2 g. ethyl chloride per 1 g. of alloy. To these bombs, there were added in addition the quantities of acetylene given in the table. The quantities of acetylene required were added as gaseous acetylene required were added as gaseous acetylene 50 contained in glass flasks with ground closures,

except that, when 0.029% or more of acetylene was added, it was dissolved directly in the ethyl chloride. Each bomb was stored on ice until all the bombs had been loaded.

The loaded bombs were placed in a tumbling machine as rapidly as possible. As each bomb was removed from the ice bath, it was given a sharp blow with a hammer to break the alloy and acetylene bulbs within the bomb. The bombs in the tumbling machine were covered with water which was raised in temperature from room temperature to 85° C. in about 9 minutes, at which temperature the bombs were tumbled for 90 minutes. After the heating period, the hot water was replaced with cold water and the bombs were tumbled for an additional 30 minutes before removal and storage on ice.

Each reaction mass was extracted with 2000 ml. benzene. Portions were titrated with iodine solution to determine the tetraethyl lead content, from which the yield was calculated.

The following table gives the yields obtained with the addition of acetone and acetylene in various amounts under the above conditions, the yields being expressed as increases over the yield obtained with 0.26% acetone and no acetylene. This base yield was 89.46% for this series of experiments.

Acetone, Wt. percent based on EtCl	Acetylene, Wt. percent based on EtCl	Percent Yield Increase
0.09	0.006	0.86
0.09	0.012	1.00
0.09	0.017	0.80
0.09	0.029	0.31
0.13	0.029	0.85
0.26	0.012	0.80
0.26	0.020	0.56
0.26	0.035	0.43
0.26	0.058	0.69
0.39	0.017	0.76
0.39	0.058	0.89
0.0	0.017	-5
0.0	0.029	-34

The last two experiments of the series are given for comparative purposes and show that acetylene alone, in the absence of acetone, seriously decreases the yields of tetraethyl lead.

It will be understood that the preceding example is given for illustrative purposes solely and that my invention is not limited to the specific embodiments disclosed therein. On the other hand, variations can be made in the proportions, conditions and equipment employed within the scope of the general description without departing from the spirit or scope of my invention.

From the preceding description, it will be ap-

parent that, by my invention, I have provided a novel and improved process for making tetraethyl lead, whereby the yields of tetraethyl lead are significantly increased. While such increase in yields do not, on their face, appear to be particularly large, they represent an important economical advantage, particularly in view of the large scale upon which tetraethyl lead is manufactured. Accordingly, I believe that my invention constitutes a valuable contribution to and advance in the art.

I claim:

1. In the process for making tetraethyl lead by the reaction of ethyl chloride on lead monosodium alloy, the improvement which comprises carrying out such reaction in the presence of from about 0.1% to about 0.4% by weight of acetone and of from about 0.005% to about 0.06% by weight of acetylene, both based on the weight of ethyl chloride present.

2. In the process for making tetraethyl lead by the reaction of ethyl chloride on lead monosodium alloy, the improvement which comprises carrying out such reaction in the presence of from about 0.1% to about 0.4% by weight of acetone and of from about 0.01% to about 0.03% by weight of acetylene, both based on the weight of ethyl chloride present.

3. In the process for making tetraethyl lead by the reaction of ethyl chloride on lead monosodium alloy, the improvement which comprises carrying out such reaction at a temperature of from about 80° C. to about 120° C., a corresponding pressure of from about 107 to about 255 pounds per square inch absolute, and in the presence of from about 0.1% to about 0.4% by weight of acetone and of from about 0.005% to about 0.06% by weight of acetylene, both based on the weight of ethyl chloride present.

4. In the process for making tetraethyl lead by the reaction of ethyl chloride on lead monosodium alloy, the improvement which comprises carrying out such reaction at a temperature of from about 80° C. to about 120° C., a corresponding pressure of from about 107 to about 255 pounds per square inch absolute, and in the presence of from about 0.1% to about 0.4% by weight of acetone and of from about 0.01% to about 0.03% by weight of acetylene, both based on the weight of ethyl chloride present.

NELSON WHITMAN.
